UNITED STATES PATENT OFFICE.

HOWARD G. CARTER, OF DETROIT, MICHIGAN.

RECTAL IRRIGATOR.

Application filed January 17, 1925. Serial No. 3,087.

This invention relates to an apparatus for flushing the bowels and like purposes and its object is to provide a construction and arrangement whereby the lower bowel may be 5 thoroughly flushed and cleansed and the cleansing fluid and all matter from the bowel immediately conducted away and deposited in a suitable receptacle without permitting the escape into the atmosphere of nauseous 10 odors.

A further object is to so combine and arrange a syringe and douche together with a receptacle to receive the offal, that the escape of odors is prevented and a thorough cleansing 15 of the bowel quickly effected with a maximum of sanitation. It is also an object to provide a douche which may be easily inserted in the rectum without danger of injury to the patient or causing undue discomfort and which will provide the necessary spray or jet and also afford an open discharge passage for the escape of the cleansing fluid and offal during the spraying operation, thus relieving the patient from 20 the discomfort which would otherwise be caused by the pressure and volume of injected fluid.

A further object is to provide a simple and easily operated apparatus providing a 30 maximum of sanitation and efficiency in operation and having other new and useful features hereinafter more fully described.

With the above and other ends in view, the invention consists in the matters herein- 35 after set forth and more particularly pointed out in the appended claims, reference being had to the accompanying drawing in which—

Figure 1 is a side elevation of an apparatus illustrative of an embodiment of the 40 invention;

Fig. 2 is a longitudinal section through a douche embodying features of the invention; and

Fig. 3 is a perspective view of locking means for a movable feed pipe and spray head of the douche.

Devices usually employed for injecting a cleansing fluid into the rectum and for other 50 and similar purposes usually comprise a jet nozzle which is inserted directly into the rectum and no provision is made for the escape of the injected fluid or offal carried by the fluid and therefore great discomfort 55 is often caused the patient by the volume and pressure of the injected fluid and the amount

which may be injected is limited as none can escape until after the removal of the douche.

Further these devices which are commonly used are unsanitary and injury to the parts 60 is liable to be caused by the insertion, and upon discharge of the cleansing fluid, the escape into the room of obnoxious odors can not be prevented. The present invention 65 contemplates the overcoming of these and other disadvantages through the provision of a douche which may be introduced easily and without danger of injury and which may be operated when in place, to open up a discharge passage for the free escape from 70 the bowel of the injected fluid and during such injection, so that the bowel will be thoroughly flushed, the operation being continued as long as necessary and the offal carried away by the flow, a suitable receptacle being 75 connected with the discharge passage to receive the out-flow and thus prevent the escape of odors.

The apparatus shown in the accompanying drawing comprises, preferably a water bag 80 1 or other suitable container for the cleansing fluid, to which bag is connected a rubber tube 2 for the conducting of the fluid to the discharge tube 3 of the douche, indicated as a whole by the numeral 4. This douche 85

includes a body or casing to which a suitable refuse receptacle 5 is connected, this receptacle being, preferably, in the form of a rubber bag having an inlet at one end and an outlet at its opposite end, the outlet being 90 tightly closed by a detachable screw cap 6 and the inlet by its connection to the downwardly and laterally projecting screw-threaded discharge end 7 of the body or casing 8 of the douche. The inlet 9 to the receptacle 5 may be formed to screw directly 95

upon the end 7 of the casing 8 as shown, or a suitable conduit, may, if found desirable, be provided for conducting the discharge into the receptacle, but in any event 100

the passage or connection will be tight and prevent the escape of odors into the atmosphere. Interposed in the tube or conduit 2 leading from the bag 1 to the douche 4, is the usual rubber bulb 10 by the compression 105 and expansion of which the fluid may be drawn from the bag and discharged with considerable force through the spray head 11 carried by the tube 3.

The body or casing 8 of the douche is exteriorly smooth and rounded, and is gradually tapered toward its open end within 110

which the spray head 11 is adapted to fit. This spray head is formed exteriorly smooth and tapered toward a smooth rounded end and is formed with a chamber 12 in said 5 end having a plurality of jet openings 13 in the rounded end of the head. This head is secured upon the open end of the tube 3 to the opposite or outer end of which the rubber conduit 2 is connected in any suitable 10 manner. The edge of the open end of the casing or shell 8 into which the head 11 fits closely, is thinned or tapered to meet the outer surface of the head and thus the outer tapering surface of the head 11 forms a substantial unbroken continuation of the tapering outer surface of the shell 8 when the head is projected into the end of the shell as shown in Fig. 2. The tube 3 extends axially of the shell 8 and out through a tubular bearing 14 formed integral with the rear end of the shell, within which bearing said tube 3 is longitudinally movable so that by moving the tube, the head 11 carried thereby may be retracted into the shell 8 as indicated 20 in dotted lines in Fig. 2, or may be projected into the open end of the shell to close the same and form a smooth rounded end for the shell. Suitable packing nuts 15 are provided around the tube where it projects through the rear end 30 of the shell to make a tight joint and prevent leakage. The outer of these nuts is formed with a longitudinally extending slot 16 having a laterally extended inner portion and on the tube 3 is a pin 17 projecting laterally therefrom to engage in said slot, as shown in Fig. 3, and lock the tube against longitudinal movement when the tube is moved to fully project the spray head 11 into the end of the shell, as shown in Fig. 2, and 40 then turned to bring the pin into the lateral end portion of the slot.

The parts being assembled as shown in Fig. 1 and with the spray head 11 projected into the open end of the shell, as shown in Fig. 2, the douche may be easily inserted in the rectum of the patient due to the smooth, rounded and continuous taper of the head and shell, and because of this smooth surface, and rounded end of the head, the danger 50 of injury to the patient is obviated. After the douche has been fully inserted, the tube 3 is released by a slight turning movement and moved longitudinally to retract the spray head into the shell and open the end of the shell. The bulb 10 is then alternately compressed and allowed to expand to draw fluid from the bag 1 and eject it with force through the jet openings 13 in the end 55 of the head 11. As these openings are directed toward the open end of the shell, the jets of fluid will be projected into the bowel of the patient, flushing and cleansing the tissues, and as the cavity fills, the water will run out through the open end of the shell, carrying with it, the offal and other matter 60 65

dislodged by the spray. This outflow can escape from the rectum of the patient only through the shell as the douche fits closely in the rectum, and as the receptacle 5 is directly connected with the outlet of the shell, the 70 discharge will flow directly into the receptacle, and as the same is tightly closed, no odors can escape. After the parts have been thoroughly cleansed, the douche is removed and the apparatus taken to a suitable 75 place where the receptacle may be emptied by removing the cap 6 from its discharge end. The discharge is therefore contained within a tight receptacle during the entire 80 operation and no obnoxious odors can escape. Further, the device is sanitary, as none of the discharge can escape except into the receptacle 5 and the operation is facilitated and the injection of fluid may be continued until the parts are thoroughly 85 cleansed without discomfiture to the patient.

Obviously changes may be made in the construction, arrangement and combination of parts, within the scope of the appended claims and I do not therefore limit myself 90 to the particular construction or arrangement shown.

Having thus fully described my invention, what I claim is:—

1. An apparatus for the purpose described 95 including a douche comprising a shell having a passage therethrough and open at its inner end, said shell being tapered toward its open inner end, a spray head having a rounded and tapered surface to fit within 100 and close said open inner end of the shell with said surface forming a continuation of said inner end of the shell when said head is projected through said opening in the shell, and means for retracting said head 105 into said shell and projecting it through said open end to close the same.

2. An apparatus for the purpose described including a douche comprising a shell having an open inner end and of smooth rounded exterior tapering toward said open end, a movable spray head to close said open end and having a smooth rounded exterior and end portion forming a continuation of the exterior of said shell when said head is 115 within said open end of the shell, said head being formed with jet openings in its rounded end and said shell having an opening at its outer end to permit free flow of water through said shell when said head is retracted from the open inner end of the shell, and means for supplying fluid under pressure to said head.

3. An apparatus for the purpose described 125 including a douche comprising a shell open at and rounded and tapered toward its inner end and provided with a discharge outlet laterally of its outer end, a spray head to fit within and close said open inner end of the shell, said head being rounded and 130

tapered to form a continuation of said inner end of the shell, and a tube carrying said head to supply fluid thereto and movable through said shell to project said head 5 through the open end of the shell and retract the same therefrom into the shell.

4. A douche as set forth in claim 3 and including means on the exterior of the outer end of the shell for locking said tube against 10 movement to hold said head projected from and within the open inner end of the shell with said end closed thereby.

5. A douche as set forth in claim 3, where- 15 in said outlet at the outer end of the shell is positioned laterally thereof and said tube extends axially of the shell and through the outer end wall thereof, said wall being provided with a bearing for said tube within 20 which bearing said tube is longitudinally movable, said tube forming a conduit to supply fluid to the head and means for moving the head into the open inner end of the shell to close the same and to retract the head into the shell out of said open end, 25 said head being provided with a jet opening to direct fluid through the open inner end of the shell when the head is retracted.

6. A douche comprising a shell of a smooth and rounded exterior having an open 30 inner end and tapered toward said end and having a laterally extending outer end portion provided with a screw-threaded end for the connection thereto of a receptacle to receive discharge from the shell, a spray head 35 of rounded and tapering exterior to fit within the open inner end of the shell and to project therefrom to form a tapering ex- 40 tension for the shell and formed with a jet opening in its rounded end, a tube for sup- plying fluid to the head and to one end of which the head is secured, the opposite end of said tube extending through the outer end wall of the shell for the attachment

thereto of a conduit for supplying fluid to the tube, the wall of said shell being pro- 45 vided with a bearing for the tube through which the tube is longitudinally movable for moving the head into and out of said open inner end of the shell, and means for locking said tube against longitudinal move- 50 ment.

7. An apparatus for the purpose described including a douche, means for supplying fluid under pressure to said douche, said douche comprising a shell having an open 55 inner end and a smooth rounded exterior tapered toward said end, a closed inner end and a laterally extending discharge outlet adjacent said outer end, a spray head having a rounded and tapering exterior to form a 60 continuation of the rounded and tapered end of the shell and provided with a jet opening in its rounded end, said head being of a di- 65 ameter to fit in said open inner end of the shell and of a length to project therefrom, a tube extending axially of the shell through the outer end wall thereof and to the inner end of which tube the head is secured, said shell wall being provided with a tubular bearing for said tube extending inwardly 70 and outwardly of said wall and within which bearing the tube is longitudinally movable to project and retract the head, means at the outer end of said bearing to form a water tight joint to prevent leakage 75 through said bearing around said tube, and locking means to lock said tube against longitudinal movement; and a receptacle comprising a bag having water tight con- 80 nection at one end with said lateral dis- charge outlet of the shell and a discharge opening at its opposite end, and a cap to close said discharge opening of the bag.

In testimony whereof I affix my signature.

HOWARD G. CARTER.
